SCORE TABLE OR THE LIKE

Richard G. Reineman, Covina, Calif., and George E. Schaefer, Muskegon Heights, Mich., assignors to Brunswick Corporation, a corporation of Delaware

Filed Apr. 11, 1960, Ser. No. 60,121

Term of patent 14 years

(Cl. D34—5)

Fig. 1 is a top plan view of a score table or the like showing our new design;

Fig. 2 is a side elevational view thereof; and

Fig. 3 is front elevational view thereof.

The dominant features of our design are shown in full lines on the drawings.

We claim:

The ornamental design for a score table or the like, as shown and described.
